UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE

Application filed April 30, 1921. Serial No. 465,894.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

The present invention relates to typewriting machines, and, more particularly, to 10 means for preventing printing against the platen while the latter is being shifted between lower and upper-case positions, so that a sluggish movement of the shifting mechanism, or a premature operation of a type-key may not result in the production of an 15 impression which is out of alignment or blurred.

It is a feature of this invention to provide 20 a simple and efficient means for accomplishing the above object with a minimum change in the construction of a standard typewriting machine. For this purpose, means are provided for preventing actuation of the 25 universal bar while the shifting operation is in progress, thus arresting the type-bars before the types can print against the platen.

Other features and advantages will hereinafter appear.

30 In the accompanying drawings,

Figure 1 is a vertical section of an Underwood standard typewriting machine, with the invention applied thereto, the platen being shown in upper-case position, and only 35 the necessary co-operating parts of the machine being shown.

Figure 2 is a view similar to Figure 1, with additional parts of the machine included, but showing the platen in lower- 40 case position.

Figure 3 is an enlarged detail, showing the invention and a few co-operating parts of the machine.

Figure 4 is a view similar to Figures 1 45 and 2, but showing the platen in an intermediate position, between upper and lower-case positions.

In the Underwood standard typewriting machine, key-levers 10 actuate bell-crank 50 11 to swing type-bars 12 upwardly and rearwardly against a platen 13, said type-bars carrying types 14 and 15 for printing in upper and lower case. Said type-bars are each provided with a shoulder 16 for striking against a universal bar 17, near the end

of a stroke, to operate the escapement-actuating frame 18, pivoted at the rear on arms 19 and 20, fixed to a shaft 21 journaled in the escapement-supporting frame 22. A rear bar 23 of the escapement-actuating frame strikes against a fixed dog 25 and rotates a shaft 29, upon which said dog is mounted, to release a movable dog 26, also mounted upon said shaft 29, from escapement-wheel 27, so that, upon return of a 65 type-bar, the carriage 30, in which the platen is mounted, will be fed to the left a distance of one letter-space by means of a pinion 31 meshing with a rack 32 on the carriage.

The platen is journaled in a platen-frame 35, which is held by arms 36, pivotally mounted at 37 on the main carriage-frame 30. For shifting the platen-frame and platen, the former is provided with a roller 38, operating on a rail 39 fixed to a swingable frame 40 pivoted at 41, said frame being operable by a finger 42 extending upwardly on a key-lever 43, similar to key-levers 10, and provided at its forward end 70 with the usual shift-key 44.

The present invention provides means for preventing actuation of the universal bar, and hence printing of the types against the platen while the platen is shifting from one 85 case to another. For this purpose, there is provided an arcuate member 50 at the end of an arm 51, pivoted on a bracket 52, fixed to the escapement-supporting frame 22, and an arm 53, fixed to shift rail 39, and having a pin-and-slot connection 54 with arm 51; so that, upon shifting the rail, arm 51, and hence member 50, will be raised, the arcuate member operating directly behind the bar 23 of the frame 18, to prevent rearward movement of the frame, and hence of the universal bar 17. Since the type-bars cannot operate sufficiently near the platen to enable the types to print thereagainst, without moving the universal bar rearwardly, it will 95 be apparent that by preventing such rearward movement of the universal bar, the types will be unable to print. The arcuate member 50 extends upwardly from arm 51 a distance such that, when shift-rail 39 is in its lowest position, the escapement-actuating frame 18 may move freely over the end thereof, as in Figures 2 and 3. While shift-rail 39 is shifting, however, the member 50 prevents any rearward movement of 100

105 member 50 prevents any rearward movement of 110

- frame 18 (see Figure 4), the arcuate member being directly behind bar 23. When shift rail 39 has reached its highest position, the frame 18 is again free to move rearwardly, such movement being permitted by a cut-out portion 55 in arcuate member 50 (see Figure 1). From the above description, it will be apparent that a type-impression cannot be made during the operation of shifting the platen, so that it is impossible for a blurred impression to be made or for the printed characters to appear out of alignment.
- Variations may be resorted to within the scope of the invention, and portions of the improvements may be used without others.
- Having thus described my invention, I claim:
1. In a typewriting machine, the combination with a platen, of a carriage therefor, types having upper and lower case characters thereon, type-bars movable with the types to the platen, an escapement mechanism for the carriage, a universal bar in the path of movement of the type-bars, to be actuated by the latter to operate the escapement mechanism, means for effecting a case-shift of the platen with respect to the types, and means connected to the case-shifting means and interposed, by movement of the latter, into the path of the universal bar to block the universal bar and thereby to prevent movement of the types to the platen when the case-shifting means is between case positions.
2. In a typewriting machine, the combination with a platen, of a carriage therefor, types having upper and lower case characters thereon, type-bars movable with the types to the platen, an escapement mechanism for the carriage, a universal bar in the path of movement of the type-bars, to be actuated by the latter to operate the escapement mechanism, a frame on the carriage shiftable with the platen between upper and lower case positions, means for effecting the case-shift of said frame, an arm pivoted to the main frame, and a connection from said arm to the shift-frame for throwing said arm into the path of movement of the universal bar, to block the latter and thereby to prevent movement of the type-bars to the platen when the shift-frame is between case positions.
3. In a front-strike typewriting machine, the combination with a platen, of a carriage therefor, types having upper and lower case characters thereon, type-bars movable upward and rearward with the types to the platen, an escapement mechanism for the carriage, a rearwardly and forwardly movable universal bar in the path of rearward movement of the type-bars, to be actuated by the latter to operate the escapement mechanism, a frame on the carriage shiftable up and down with the platen between upper and lower case positions, means for effecting the case-shift of said frame, an arm pivoted to the main frame and interposable into the path of rearward movement of the universal bar, and a connection from said arm to the shift-frame for throwing said arm into the path of rearward movement of the universal bar, to block the latter and thereby to prevent movement of the type-bars to the platen when the shift-frame is between case positions.
4. In a typewriting machine, the combination with a platen, of a carriage therefor, types having upper and lower case characters thereon, type-bars movable with the types to the platen, an escapement mechanism for the carriage, a universal bar in the path of movement of the type-bars, to be actuated by the latter to operate the escapement mechanism, a frame on the carriage shiftable with the platen between upper and lower case positions, means for effecting the case-shift of said frame, an arm pivoted to the main frame, and a connection from said arm to the shift-frame for throwing said arm into the path of movement of the universal bar, to block the latter and thereby to prevent movement of the type-bars to the platen when the shift-frame is between case positions.
5. In a typewriting machine, the combination with a platen, of a carriage therefor, types having upper and lower case characters thereon, type-bars movable with the types to the platen, an escapement mechanism for the carriage, a universal bar in the path of movement of the type-bars, to be actuated by the latter to operate the escapement mechanism, a frame on the carriage shiftable with the platen between upper and lower case positions, means for effecting the case-shift of said frame, a segmental stop pivoted to the main frame, and a connection from said stop to the shift-frame for throwing said stop into the path of movement of the universal bar, to block the latter and thereby to prevent movement of the type-bars to the platen when the shift-frame is between case positions; the segmental stop having a recess therein which registers with and permits movement of the universal bar when the shift-frame reaches upper-case position.
6. In a typewriting machine, the combination with a platen, of a carriage therefor, types having upper and lower case characters thereon, type-bars movable with the types to the platen, an escapement mechanism for the carriage, a universal bar in the path of movement of the type-bars, to

be actuated by the latter to operate the escapement mechanism, means for effecting a case-shift of the platen with respect to the types, and means connected to the case-shifting means to engage the universal bar, and thereby to prevent full movement of the type-bars, while the case-shifting means is being operated.

7. In a front-strike typewriting machine, in combination, a carriage, a platen-frame having a platen journaled therein, an escapement mechanism for said carriage, type-bars mounted in said machine, type-bar operating mechanism to cause said type-bars to print against the platen, said type-bars having upper and lower-case types, means for shifting said platen between upper and lower-case positions, a universal bar movable rearwardly by said type-bars near the end of a stroke for actuating said escapement mechanism, and a stop member pivotally mounted on the machine and connected to said shifting means and interposed by said shifting means in the path of movement of said universal bar during the shifting operation, to prevent rearward movement of said universal bar and arrest said type-bars before reaching the platen while the latter is being shifted, said stop member being out of the path of movement of the universal bar in the extreme lower position of the shifting means, said stop having a cut-out portion which is opposite said universal bar in the extreme upper position of the shifting means to permit rearward movement of the universal bar in said extreme upper position of said shifting means.
8. In a front-strike typewriting machine, in combination, a carriage, a platen-frame having a platen journaled therein, an escapement mechanism for said carriage, type-bars mounted in said machine, type-bar operating mechanism to cause said type-bars to print against the platen, said type-bars having upper and lower-case types, means for shifting said platen between upper and lower-case positions and comprising a shift-rail, a universal bar movable rearwardly by said type-bars near the end of a stroke for actuating said escapement

mechanism, an arm pivotally mounted on said machine, a stop member on said arm, a second arm fixed to said shift-rail, a connection between said arms so that the stop member moves simultaneously with said shifting means into the path of movement of said universal bar during the shifting operation, to prevent rearward movement of said universal bar and arrest said type-bars before reaching the platen while the latter is being shifted.

9. In a typewriting machine, the combination with a platen, of a carriage therefor, types having upper and lower case characters thereon, type-bars movable with the types to the platen, an escapement mechanism for the carriage, a universal bar in the path of movement of the type-bars to be actuated by the latter to operate the escapement mechanism, means for effecting a case-shift of the platen with respect to the types, and a pivoted linkage supported from the case-shifting means and the machine-frame and swingingly interposed, by movement of the former, into the path of the universal bar to block it and thereby to prevent movement of the types to the platen when the case-shifting means is between case positions.

10. In a typewriting machine, the combination with a platen, of a carriage therefor, types having upper and lower case characters thereon, type-bars movable with the types to the platen, an escapement mechanism for the carriage, a universal bar in the path of movement of the type-bars to be actuated by the latter to operate the escapement mechanism, means for effecting a case-shift of the platen with respect to the types, and a pivoted linkage connected between the case-shifting means and the machine-frame to engage the universal bar, and thereby to prevent full movement of the type-bars while the case-shifting means is being operated.
